UNITED STATES PATENT OFFICE.

ANDREW D. HULQUIST, OF CHICAGO, ILLINOIS, ASSIGNOR TO J. S.
McDONALD, OF CHICAGO, ILLINOIS.

LOCK FOR THE ADJUSTABLE BACKS OF LOOSE-LEAFED LEDGERS, ACCOUNT-BOOKS, RECORD-BOOKS,
FILES, &c.

No. 807,557.

Specification of Letters Patent.

Patented Dec. 19, 1905.

Application filed January 25, 1904. Serial No. 190,624.

To all whom it may concern:

Be it known that I, ANDREW D. HULQUIST, a citizen of the United States, and a resident of Chicago, in the county of Cook and State of Illinois, have invented certain new and useful Improvements in Locks for the Adjustable Backs of Loose - Leafed Ledgers, Account-Books, Record-Books, Files, &c., of which the following is a full, clear, and exact description.

10 My invention relates to books, &c., having covers and backs between which the leaves can be removably secured and which are capable of being moved bodily to and from each other and locked or unlocked in any position 15 to which they may be adjusted simply by being laid on one side or the other and compressed.

The object of my invention is to reduce the construction of such a lock to the simplest 20 form possible consistent with its perfect operation and economical manufacture. This I accomplish by the means hereinafter fully described and as particularly pointed out in the claims.

25 In the drawings, Figure 1 is a longitudinal central section through my invention, showing the ends of the parts thereof secured to the clamping-plates of the back of the book, which are also shown in section. Fig. 2 is a 30 view similar to Fig. 1, but with the book reversed, so as to illustrate the changed position of the parts of the locking devices. Fig. 3 is a detail view illustrating a longitudinal central section of the bolt of said lock; and 35 Fig. 4 is a similar view, but with said bolt turned on its axis at right angles to the position thereof shown in Fig. 3.

In the drawings, A and B represent the clamping-plates of the adjustable back of a 40 book adapted to removably retain loose leaves. The rear edges of these clamping-plates have stiff lapping curtains a and b, respectively, that protect the rear edges of the leaves, and their front edges have the covers of the book 45 suitably secured thereto.

Secured at right angles to the inner flat side of clamping-plate A by means of a screw a' is a bolt C. This screw extends through a countersunk opening in plate A and is tapped 50 longitudinally and centrally into the adjacent end of said bolt, so that by the use of a screw-driver said bolt could be turned in the direction of the pitch of the screw. If desired,

however, the bolt could be so fastened in clamping-plate A as to be immovable. The 55 unsecured end of bolt C is preferably made slightly greater in diameter than the remainder of its length, forming a head g, and a diametrical slit c is made longitudinally in said end that extends from the extremity of the 60 bolt past the shoulders of said head. Loosely pivoted in this slit c by means of a pin d, extending diametrically through head g at right angles to the plane of slit c, is a pawl D, the contours of the preferred shape of which corresponds to those of a central section of a truncated cone. The pivotal pin d strikes through the truncated angle of the pawl, and the length of the base-line of said pawl is slightly greater than the diameter of the body 70 of the bolt, substantially as shown in Fig. 4 of the drawings.

Secured to and projecting at right angles from plate B in alinement with bolt C is a tubular counterpart or case E, the inner surface 75 h of which is corrugated or grooved in a suitable manner. These corrugations may be either spiral, as shown in the drawings, or concentric rings; but the former is preferable on account of the desirability of further compressing the loose leaves by revolving the bolt after the initial compression. This case has one end secured in plate B, preferably by being tapped into it and then its end edges spread in any suitable manner and has the diameter 80 of its opposite unsecured end e reduced to prevent the withdrawal of the head g of the bolt. This construction, however, while preferable need not be adopted.

The operation of my invention is simple. 90 Supposing the book to be in the position shown in Fig. 1 of the drawings and that the leaves or other matter contained between the covers be sufficient to expand the book and separate the clamping-plates. Under these conditions 95 when by external pressure the clamping-plates have been pushed toward each other as far as they will go the pawl or dog D, whose gravity causes it to move on its axis to the one side or the other, will when the pressure is 100 removed catch against the ridges of the corrugations h of the case and prevent the further separation of the clamping-plates. Now if the position of the book is reversed and it is desired to separate the covers of the book, 105 by exerting pressure enough the said clamp-

ing-plates can be moved toward each other slightly, sufficient to enable the dog D to gravitate out of engagement with the corrugated inner surface of the case and into the 5 position shown in Fig. 2 of the drawings, and thus permit the clamping-plates to separate (within the limits of their outward movement) according to the outward pressure of the contents of the book.

10 What I claim as new is—

1. In a loose-leaf binder comprising clamping-plates, a rotatable bolt secured to and projecting from one of said plates, a tube secured to the other plate into which said bolt enters 15 which has transverse spiral corrugations on its inner surface, and a gravity-controlled pawl pivoted at its end nearest the extremity of said bolt and having two engaging points at its opposite end one on one side and the other 20 on the other side of the axis of said bolt which are adapted to engage the corrugations of the tube on one side or the other of the bolt.

2. In a loose-leaf binder comprising clamping-plates, a rotatable bolt secured to and projecting from one of said clamping-plates having 25 an enlarged head at the unsecured end thereof, a tube secured to the other plate having the diameter of the opening in its unsecured end into which said bolt enters restricted and having transverse spiral corrugations 30

on its inner surface, and a pawl pivoted at its end nearest the extremity of said bolt and having two engaging points at its opposite end one on one side and the other on the other side of the axis of said bolt which are adapted to engage the corrugations of the tube on one side or the other of the bolt. 35

3. In a loose-leaf binder comprising clamping-plates, a rotatable bolt secured to and projecting from one of said clamping-plates having a head on its unsecured end which is provided with a longitudinal slit therein, a tube secured to the other plate having the diameter of the opening in its unsecured end into which said bolt enters restricted and having trans- 40 verse spiral corrugations on its inner circumference, and a gravity-controlled pawl pivoted at its end nearest the extremity of said bolt within said slot and having two engaging points at its opposite end one on one side and the other on the other side of the axis of said bolt which are adapted to engage the corrugations of the tube on one side or the other of the bolt. 45

In testimony whereof I have hereunto set 50 my hand this 14th day of January, 1904.

ANDREW D. HULQUIST.
